United States Patent Office

Des. 211,891

Patented Aug. 6, 1968

211,891

GOBLET OR THE LIKE

James L. Wentzel, Cottage Grove, Minn., assignor to Plastics, Inc., St. Paul, Minn., a corporation of Minnesota

Filed Oct. 18, 1967, Ser. No. 9,058

Term of patent 14 years

(Cl. D36—8)

FIG. 1

I claim:

The ornamental design for a goblet or the like, as shown.
